(57) **CLAIM**

I claim, the ornamental design for an ornamental magnet, as shown and described.

DESCRIPTION

FIG. 1 is a perspective view of the ornamental magnet of the present invention;

FIG. 2 is top plan view of the ornamental magnet;

FIG. 3 is a bottom plan view of the ornamental magnet;

FIG. 4 is a front elevational view of the ornamental magnet;

FIG. 5 is a rear elevational view of the ornamental magnet;

FIG. 6 is a left side elevational view of the ornamental magnet; and,

FIG. 7 is a right side elevational view of the ornamental magnet.
